(57) **CLAIM**

The ornamental design for a display screen or portion thereof with graphical user interface of X-ray computed tomography device as shown and described.

DESCRIPTION

The FIGURE is a front view of a display screen or portion thereof with graphical user interface of X-ray computed tomography device of our new design.

The dot-dash broken line in the drawing illustrates unclaimed portions of the display screen and unclaimed portions of the graphical user interface that form no part of the claimed design. The dashed broken lines illustrate portions of the graphical user interface that form no part of the claimed design.
